ROTARY BORING BIT

Clarence E. Reed, Wichita, Kans., assignor to
 Chicago Pneumatic Tool Company, New York,
 N. Y., a corporation of New Jersey

Application May 19, 1931, Serial No. 538,471

38 Claims. (Cl. 255—71)

This invention relates to earth boring apparatus and more particularly to rotary roller bits for deep well drilling.

One object of the invention is to provide an improved roller bit for drilling rock and other hard formations. Another object is to provide for complete flushing of the drill hole and ample clearance between the walls of the hole and the drill stem in order that the cuttings may be carried away at once and not interfere with the drilling speed. Another object is to cut the entire area at the bottom of the drill hole. Still another object is to effect fast drilling while maintaining a straight hole. Other objects will be apparent from the detailed description which follows.

The invention comprises a bit head having an eccentric projection upon which all of the cutting elements are mounted. These elements are disposed transversely of the bit head and in the same vertical central plane. The bit head projection has studs extending outwardly therefrom with an upward inclination in the said vertical central plane. The studs are of unequal length but extend beyond the walls of the bit head on opposite sides thereof to a substantially equal extent and at substantially the same angle relative to the axis of the head. Above the studs the bit head is undercut to permit the mounting of roller cutters on the studs and intermediate the studs the sides of the bit head projections parallel to the vertical plane of the cutters are reduced along arcuate and forwardly tapered lines to provide spaces for flushing out the cuttings. Outlets are symmetrically disposed relative to the axis of the head for discharging flushing fluid into the undercuts above the stud and another outlet is disposed axially of the bit head projection but off center relative to the axis of the bit head. The last-named outlet opens into a recess for vertically disposed roller cutters for engaging the bottom of the hole adjacent its center.

In order to illustrate the invention one concrete embodiment thereof is shown in the accompanying drawing in which:

Fig. 1 is a side elevational view of the complete bit with the lower portion shown in vertical section;

Fig. 2 is a similar view on a smaller scale of the bit head or body alone, the lower portion of which is in section substantially on the line 2—2 of Fig. 1; and

Fig. 3 is a bottom plan view of the bit head on the same scale as Fig. 2.

The embodiment of the invention chosen for

the purpose of illustration comprises a bit head 4 having the conventional reduced and tapered threaded upper end 5 for attachment to a reamer body or directly to the drill stem. The opposite or working end of the bit head has an integral projection or extension 4a which is eccentrically disposed relative to the bit body as clearly indicated in Fig. 3. The projection 4a carries the cutters, all of which are disposed in the same vertical plane, as indicated in Fig. 1. The bottom end of eccentric projection 4a is deeply recessed, as indicated at 5, to receive and mount on an axis transverse to the axis of the bit head, a series of roller cutters 6, 7 and 8. These cutters are rotatably mounted upon a bearing sleeve 9 having an eccentric head or flange 9a which fits one of the counterbores or seat recesses 5a at the opposite ends of cutter recess 5. The purpose of the eccentric head or flange 9a is to prevent bearing sleeve 9 from turning. The opposite end of sleeve 9 carries an eccentric washer 10 which fits the opposite seat recess 5a. A retainer pin 11 extends through the bore of bearing sleeve 9 and the ends thereof are received in aligned bores 12 in the end portions or extensions 14 and 15 of eccentric projection 4a which define the limits of recess 5. Cutters 6, 7 and 8 may be spaced on bearing sleeve 9 as desired, as, for example, by one or more spacing rollers 13.

Upon the exterior of end portions 14 and 15 of eccentric projection 4a are disposed outwardly extending studs 14a and 15a respectively in the plane defined by the axis of the bit head and the axis of cutters 6, 7 and 8. These studs are of unequal length, stud 15a being longer than stud 14a, but both extend beyond the vertical projection of bit head 4, as clearly indicated in Figs. 1 and 3. Moreover, the studs are in angular relation to the axis of the bit head, as at substantially the same acute angle. Above each of the studs the bit head is undercut as indicated at 4b and 4c to provide for the mounting of cutters on the studs. In the form shown short stud 14a carries a single roller 16 while the longer stud 15a carries two rollers, namely 17 and 18. Removable bearing members are provided for the rollers as thrust washers 19 which are slipped over studs 14a and 15a to engage end portions 14 and 15 defining recess 5. These washers cover the bores in the end portions receiving the ends of retainer pin 11 so that withdrawal of the latter is prevented. The remainder of the bearing area for cutters 16, 17 and 18 is provided by bearing nuts 20 and 21 in threaded engagement with studs 14a and 15a respectively. These nuts have

stop flanges 20a and 21a respectively opposed to stops provided by thrust washers 19. Any suitable means (not shown) may be provided for locking bearing nuts 20 and 21 in place. To assist in softening the formation, to clear the cutters of disintegrated material and to wash out the cuttings, flushing fluid is directed from the central bore of the drill stem and of drill head 4 by a passage 22 offset from the axis of the head into

5 recess 5 and by inclined side passages 23 and 24 into undercuts 4b and 4c over the stud cutters.

To provide space for flushing out the cuttings from the bottom of the hole the eccentric projection 4a is reduced by arcuate and downwardly 10 converging recesses or cut away portions 25 and 26, as clearly indicated in Figs. 2 and 3. The angular position of studs 14a and 15a relative to the axis of the drill bit and the projection of the same beyond the sides of the latter cause the 15 outer stud cutters 16 and 18 to cut a hole of much greater diameter than that of the bit head so that ample clearance is provided for the upward passage of the flushing fluid and the entrained cuttings. This construction together with 20 the mounting of all of the cutters in a single vertical plane makes for exceptionally fast penetration even in very hard formations since the cuttings can be washed out freely even when in the form of rather large chips and lumps.

25 30 By projecting the portion of the bit on one side of the vertical axis (substantially the line 2-2 of Fig. 1) on the other side, it will be found that the arrangement of cutters illustrated in Fig. 1 is such as to cut the entire area of the drill 35 hole. Cutter 6, which has its inner end substantially on the vertical axis of the bit, will cut the area corresponding to the space left by spacing roller 13. Cutters 7 and 8 cut the space between cutters 6 and 17. Cutter 17 takes care of 40 the space between cutters 8 and 16, and cutter 16 the space between cutters 17 and 18. Although the appearance of the complete bit as viewed in Fig. 1 creates an impression of unbalance, this is nullified by the fact that the actual 45 area operated on by the cutters on both sides of the vertical axis of the head is substantially the same, and by the positioning of the cutters in a single vertical central plane. The bit cuts a straight hole and the angular position of the side 50 cutters on the studs together with ample clearance from flushing out the cutting insures fast penetration.

55 While the invention has been herein disclosed in what is now considered to be a preferred form, it is to be understood that the invention is not limited to the specific details thereof but covers all changes, modifications and adaptations within the scope of the appended claims.

60 I claim as my invention.

65 1. A bit for rotary drilling including a bit head having an eccentric projection with a recess in its lower face, means mounting roller cutters in said recess on an axis transverse to the axis of the bit head, and means on the exterior of said projection for mounting additional roller cutters comprising studs angularly disposed relative to the axis of the bit head, all cutter axes being in the same vertical plane and the rollers cutting the entire area of the bottom of the drill hole.

70 2. A bit for rotary drilling including a bit head having an eccentric projection with a recess in its lower face, means mounting roller cutters in said recess on an axis transverse to the axis of the bit head, and means on the exterior of said

projection for mounting additional roller cutters comprising studs inclined at an acute angle to the axis of the bit head, said bit head being undercut above said studs to provide for the mounting of rotary cutters on the latter and having openings for discharging flushing fluid into said recess and into said undercuts all cutter axes being in the same vertical plane and the rollers cutting the full area of the drill hole.

75 3. A rotary boring bit including a bit head having an eccentric projection with a recess in its lower face, a bearing sleeve mounted in said recess, roller cutters on said sleeve, a retainer pin extending through said sleeve and having its ends received in bores in the end portions of said projection which limit said recess, studs extending from said end portions above said bores, and means on said studs preventing withdrawal of said pin.

4. A rotary boring bit including a bit head having an eccentric projection with a recess in its lower face, a bearing sleeve mounted in said recess, roller cutters on said sleeve, a retainer pin extending through said sleeve and having its ends received in bores in the end portions of said projection which limit said recess, studs extending from said end portions above said bores, and means including cutters rotatably mounted on said studs preventing withdrawal of said pin.

45 5. A rotary boring bit including a bit head having an eccentric projection with a recess in its lower face, a bearing sleeve mounted in said recess, roller cutters on said sleeve, a retainer pin extending through said sleeve and having its ends received in bores in the end portions of said projection which limit said recess, studs extending from said end portions above said bores, bearing members on said studs providing opposed stops, cutters rotatably mounted on said last-named members and maintained in place by said stops, said last-named bearing members extending across the bores in said end portions to prevent withdrawal of said pin.

55 6. In a rotary bit, a bit head, a roller cutter organization comprising an eccentric member mounting roller cutter elements, whose axes are all in the same vertical plane, for rotation on and for cutting the entire area of the bottom of the hole, the said eccentric member having cutter elements mounted in a recess in its lower face, and at opposite sides thereof cutter elements mounted on spindles oppositely inclined to the axis of the bit head in planes converging in the head, the peripheral cutters tracking each other and the cutter element in the recess being non-tracking.

60 7. In a roller cutter organization, a bit head, a series of cutters supported thereby and so arranged as to cut the entire area at the bottom of the hole and including spaced cutter elements oppositely inclined in planes converging in the bit head, and intermediate thereof cutters spaced to cut each singly a zone progressively and outwardly from the bit axis, the axes of all said cutter elements being disposed in the same vertical plane, and a combination spindle member having spindle portions for the end cutters of the series, said spindle portions being inclined toward the axis of the bit head.

65 8. In a roller bit, a bit head having a side cutter on each side thereof, substantially cylindrical cutters intermediately disposed between the side cutters and set one to one side of the axis of the bit head to cut in a plane lower than the side cutters, and another adapted to cut on the bottom of

the hole outwardly from the cutter at the bit axis, the axes of all cutters being in the same vertical plane, the cutters being adapted to cut the entire area of bottom of hole, a bore in the bit head terminating in a plurality of outlets, some outlets terminating directly above and washing the cutter teeth and another outlet being offset in relation to the bit axes.

9. In a rotary bit, a head, a roller cutter organization comprising an eccentric member mounting roller cutter elements adapted to cut the entire area of the bottom of the bore hole, the said eccentric member having cutter elements at each side thereof on spindles integral therewith and oppositely inclined to the axis of the bit head in planes converging in the head, the peripheral cutters tracking each other and the intermediate cutters being non-tracking and spaced to cut progressive zones outwardly from the bit axis, all of the intermediate cutters having axes in the same vertical plane as the axis of one of the peripheral cutters.

10. In a roller bit cutter organization, a bit head, a series of cutters supported thereby and so arranged as to cut the entire area of the bottom of a bore hole and including spaced cutter elements oppositely inclined in planes converging in the bit head and intermediate cylindrical cutters spaced to cut each singly a zone progressively from the bit axis outwardly, the axes of all said cutter elements being disposed in the same vertical plane and the intermediate cutters being each mounted to rotate on a horizontal axis, and a combination spindle supporting member having spindles disposed at an angle to each other and including a spindle integral with and at right angles from a face on the spindle supporting member.

11. In a roller cutter unit, a bit head, roller cutters adapted to cut the entire area of the bottom of the bore hole and with all axes in the same vertical plane, and spaced on each side of the vertical axis of the bit head, one cutter adjacent the axis on one side, radial thereto and in non-tracking relationship, inclined peripheral cutters in planes converging in the bit head, said cutters tracking each other, and a series of intermediate cutters all having substantially cylindrical cutting surfaces and open spaces intermediate the peripheral cutters.

12. In a roller bit, a cutter organization comprising spaced cutter elements having all axes in the same vertical plane, the peripheral cutters being inclined and arranged to track each other, an intermediate group of roller cutters in non-tracking relationship, and spindle support means comprising a member including thereon the spindles of both peripheral cutters and the intermediate cutters, the organization being adapted to cut the entire area of the bottom of the bore hole.

13. A roller bit comprising side cutters whose axes incline downwardly and inwardly towards the longitudinal axis of the bit, said cutters being adapted to cut a peripheral area at the bottom of the bore hole, roller cutter means whose axis is radial to and at right angles to the longitudinal axis of the bit and positioned to cut a central area of the bottom of the bore hole, and roller cutter means having its axis inclined downwardly and inwardly towards the longitudinal axis of the bit, said last-mentioned roller cutter means being positioned to cut an annular area extending completely from the central to the peripheral areas and in non-tracking rela-

tionship to any other cutter means, and having its axis in the same vertical plane as said radial axis.

14. A roller bit as defined in claim 13 in which the axes of all cutter means are disposed in the same radial plane.

15. In a roller bit, side cutters inclined in planes converging in the bit, a radial central cutting element having its axis in a horizontal plane, and an intermediate cutter element whose axis is inclined to the bit axis, the cutters cutting the entire area of the bottom of the bore hole, said central cutting element having its axis in the same vertical plane as the axis of one of the side cutters.

16. In a roller bit having a projection at its lower end, spindles at the outer sides of said projection mounting roller cutters on axes inclining downwardly and inwardly to the vertical axis of said bit, a recess in the lower face of said projection, in which recess is mounted a plurality of roller cutters to rotate on axes in a horizontal plane, the last-named roller cutters having spindle support at an inner side of the said projection limiting the recess, said last-named roller cutters cutting the area intermediate that cut by the inclined cutters and being mounted on axes in the same diametrical plane as the axis of an inclined cutter.

17. In a roller bit according to claim 16, the bearing for cutters on horizontal axes being in form an eccentric.

18. In a roller boring drill, side cutters inclined in planes converging in the drill to rotate on axes inclining downwardly and inwardly towards the drill axis, and centrally positioned cutters having axes in a horizontal plane, being mounted on an eccentric bearing, all cutters being side by side, all centrally positioned cutters having axes in the same vertical plane as the axis of one of the side cutters.

19. A roller bit comprising a bit head, an eccentric projection depending therefrom, a plurality of roller cutters mounted to rotate on axes all in the same transverse vertical plane and adapted to cut the entire area at the bottom of the bore hole, said cutters being mounted upon spindles supported by the eccentric projection, the eccentric projection being recessed at its lower end to receive one of said cutter supporting spindles, the said projection having a plurality of said spindles extending outwardly and upwardly from its sides.

20. A bit including a bit head having an eccentric projection, spindles at the outer sides of said projection mounting side roller cutters to rotate on axes inclining downwardly and inwardly toward the vertical axis of said head, a recess in the lower face of said projection, in which recess is mounted a plurality of roller cutter elements to rotate on an axis radial to the bit axis and in the same vertical plane as one of the side cutters.

21. A bit for rotary drilling including a bit head having at its lower end an eccentric member mounting a series of cutters arranged for cutting the entire area of the bottom of the bore hole, some of said cutters being in a substantially central position and others of said cutters being in inclined side positions, said series being adapted to cut progressively and outwardly from the bit axis, the eccentric member having integral spindle portions at each side thereof and being integral with the bit head, all cutter axes being in the same transverse vertical plane, the

- axes of the end cutters of the series being inclined to the axis of the bit head, and each of the cutters in the central position being mounted to rotate on a horizontal axis.
- 5 22. In a roller bit, a bit head having side cutters inclined in planes converging in the head, an intermediately positioned cutter group having cutters disposed on opposite sides of the axis of the bit head, with one axis of the said group 10 at right angles to the axis of the bit head, the axes of all cutters of the group being in the same transverse vertical plane, a bore in the bit head terminating in a plurality of outlets to wash the cutters, and spindle support means comprising a 15 member adapted to carry each side cutter and intermediately positioned cutter group, the cutters being adapted to cut the entire area of the bottom of the hole, and at least one of the cutters intermediate the side cutters having its axis 20 inclined to the vertical axis of the bit.
23. A roller cutter unit having cutters adapted to cut the entire area of the bottom of the hole and comprising inclined side cutters, the axes of which incline downwardly and inwardly, 25 an intermediate cutter group of cylindrical shaped cutters having all their axes in the same vertical plane as one of the side cutters, the unit having spindle supports between the inclined cutters and said intermediate group.
- 30 24. A roller cutter unit according to claim 23, the intermediate cutters being spaced apart and cutting the area between the side cutters in non-tracking relationship, one of the cutters having its axis inclined to the bit axis, the last-named 35 cutter being next adjacent one of the side cutters.
25. In combination in an earth boring drill, a bit head, side cutters rotating in planes converging upwardly in the bit head, and adapted to 40 maintain the gauge of the hole, and other cutters having all their axes in the same vertical plane intermediate the side cutters, and inclined to each other at an acute angle, the cutters being positioned to cut substantially the entire 45 area at the bottom of the hole.
26. In earth boring apparatus, a roller bit comprising a bit head, one or more rotatable side cutters each mounted to rotate on an inclined axis and projecting beyond the periphery of the 50 bit head to maintain the gauge of the hole, one or more central cutters mounted to rotate on a horizontal axis to roll over a central area which includes the axis of the bit, and an intermediate roller cutter mounted to rotate on an inclined 55 axis in the same vertical plane as said horizontal axis and adapted and disposed to roll over a circular path closely surrounding said central area but spaced from the periphery of the bore hole; said intermediate roller cutter being in 60 non-tracking relationship with respect to any other cutter.
27. In earth boring apparatus, a roller bit comprising a bit head, one or more rotatable side cutters each mounted to rotate upon an inclined 65 axis and projecting beyond the periphery of the bit head to maintain the gauge of the hole, one or more central cutters mounted on a horizontal axis to roll over a central area which includes the axis of the bit, and an intermediate roller cutter 70 mounted to rotate on an inclined axis and adapted and disposed to roll over a circular path surrounding said central area but spaced from the periphery of the bore hole, the axes for the intermediate and the central cutters being in the 75 same plane.
28. A roller cutter unit for an earth boring drill comprising a body portion having a recess in its lower face and a roller cutter mounted therein, said body portion having inclined side cutter spindles projecting outwardly and upwardly therefrom and roller cutters mounted on the spindles, the said body portion being positioned to one side of the axis of the unit and the inclined spindles being of different lengths.
29. As an article of manufacture, a roller cutter 10 carrier having a roller cutter receiving recess therein and spindles projecting outwardly and upwardly from said carrier, said spindles being of different lengths, said carrier having a body portion positioned eccentrically with respect to 15 the axis of rotation.
30. A bit for rotary drilling including a bit head having an eccentric projection, and roller cutters on said projection arranged some in substantially horizontal central and others in inclined side positions for cutting the entire area at the bottom of the drill hole, the cutters in the side positions having their axes inclined and being arranged to track each other, all cutters in the central position having axes in the same vertical plane as the axis of one of the side position cutters.
31. A bit for rotary drilling including a head having an eccentric projection, means on said projection mounting roller cutters for rotation 30 about axes all disposed in the same vertical plane, one of said axes being in a horizontal plane transverse to the axis of the bit head, and the other axes inclined relative to the axis of the bit head, the inclined axes extending above and 35 diverging from said transverse axis, the cutters being adapted to cut the entire area of the bottom of the hole.
32. A roller bit comprising a bit head, an eccentric projection carried thereby, roller cutter 40 means mounted in a recess in the lower face of said eccentric projection to rotate on a horizontal axis and positioned to cut a central area of the bottom of the bore hole, one or more side cutters carried by the eccentric projection for maintaining the gauge of the hole, and additional roller cutter means mounted to rotate on an axis inclining downwardly and inwardly toward the longitudinal axis of the bit, said additional roller cutter means being positioned to enlarge the area 45 cut by the first-mentioned means, and being in non-tracking relationship to any other cutter means.
33. A roller bit comprising a bit head having at its lower end a pair of depending walls defining 55 therebetween a downwardly open recess, a spindle positioned in said recess and extending transversely to the bit axis and supported at its ends by said walls, a central group of roller cutters mounted on said spindle, other spindles supported by said bit head and extending upwardly and outwardly from said walls, inclined roller cutters rotatably mounted on said other spindles, each cutter in the central group having an axis 60 in the same vertical plane as the axis of an inclined cutter, said walls being positioned at different distances from the bit axis, one wall and one of the central group cutters being equidistant from the bit axis on opposite sides, whereby said last-named cutter cuts the area passed over 65 by said one wall, and one of the inclined cutters being positioned to cut the area passed over by the other wall.
34. A well drill including a head, a plurality of cutter shafts on the lower end thereof, two outer 70

cutter shafts being inclined outwardly and upwardly in the same vertical plane, cutters on said outer shafts the periphery of each cutter being tapered to converge at a point outside the wall of the hole being drilled, one of said outer cutters being longer than the other.

35. A roller bit comprising a bit head, an eccentric projection depending therefrom, having spindles projecting from its opposite sides and a downwardly opening recess at its lower end, a spindle supported within said recess, roller cutters mounted on said spindles, positioned to cut the entire area at the bottom of the bore hole, the spindles having their axes in the same transverse

vertical plane.

36. A roller bit comprising a bit head, an eccentric projection depending therefrom, having spindles projecting from its opposite sides and a downwardly opening recess at its lower end, a spindle supported within said recess, roller cutters mounted on said spindles, positioned to cut the entire area at the bottom of the bore hole, one of said cutters being mounted on the spindle supported within said recess and disposed adjacent the axis of the bit, the spindles having their axes in the same transverse vertical plane.

37. A roller bit comprising a bit head, an eccentric projection depending therefrom, a plu-

rality of spindles supported by said eccentric projection, and having their axes all disposed in the same transverse vertical plane, cutters mounted on said spindles and adapted to cut the entire area at the bottom of the hole and including roller cutters mounted on opposite lateral faces of the eccentric projection, one of said spindles being mounted within a recess in the lower end of the eccentric projection, the bit head being provided with a flushing fluid conduit having outlets terminating above the eccentric projection on each side thereof and above the cutters mounted upon the opposite lateral faces of said projection.

38. A roller bit comprising a bit head, an eccentric projection depending therefrom, a plurality of spindles supported by said eccentric projection, and having their axes all disposed in the same transverse vertical plane, cutters mounted on said spindles and adapted to cut the entire area at the bottom of the hole and including roller cutters mounted on opposite lateral faces of the eccentric projection disposed about axes inclined downwardly and inwardly, one of the spindles being mounted within a recess in the lower end of the eccentric projection.
